CLAIM

The ornamental design for a sanitary key bow, as shown and described.

DESCRIPTION

FIG. 1 is a front, top, left perspective view of a sanitary key bow showing the new design.

FIG. 2 is a front, top, right perspective view of the sanitary key bow of FIG. 1.

FIG. 3 is a top view of the sanitary key bow of FIG. 1.

FIG. 4 is a front view of the sanitary key bow of FIG. 1.

FIG. 5 is a bottom view of the sanitary key bow of FIG. 1.

FIG. 6 is a rear view of the sanitary key bow of FIG. 1.

FIG. 7 is a left-side view of the sanitary key bow of FIG. 1; and,

FIG. 8 is a right-side view of the sanitary key bow of FIG. 1.

The broken lines indicate unclaimed portions of the article and form no part of the claimed design.
